CLAIM

The ornamental design for a rail mounted light source, as shown and described.

DESCRIPTION

FIG. 1 is a front, top, left side perspective view of our design.

FIG. 2 is a front, top, right side perspective view thereof.

FIG. 3 is a front elevation view thereof.

FIG. 4 is a left elevation view thereof.

FIG. 5 is a right elevation view thereof.

FIG. 6 is a top view thereof; and,

FIG. 7 is a bottom view thereof.

The dashed lines in the figures are included for the purpose of illustrating portions of the article and form no part of the claimed design.

1 Claim, 7 Drawing Sheets(56)
